POLISHING GUARD

Jack G. McNeil, Fort Leonard Wood, Mo.

Application February 27, 1952, Serial No. 273,763

4 Claims. (Cl. 51—265)

1

The present invention relates to polishing guards for use in polishing buttons and insignia attached to garments, uniforms and the like by either a single or spaced attaching means, and the invention aims generally to improve prior guards for such purpose.

Many garments and uniforms both for personnel of the armed forces and civilians have attached thereto metal buttons, insignia and the like, which require periodic polishing for best appearance. Buttons are commonly attached to the garments or uniforms by a single attaching means, as by sewing or by an attaching member secured to the button and piercing the garment. Insignia frequently have a plurality of spaced attaching means formed thereon and adapted to pierce the garment, and the spacing between such spaced attaching means varies in different types and sizes of insignia. Therefore, a guard means which will effectively protect the fabric of the garment from soilage by the polishing agent should be adapted to embrace either a single attaching means or a plurality of variously spaced attaching means.

The primary object of the present invention, therefore, is to provide an improved polishing guard so constructed and arranged as to readily encompass either a single attaching means or a plurality of variously spaced attaching means as may be presented for cleaning or polishing.

With the above and other objects in view the invention may be fully understood by reference to the accompanying drawings and annexed specification illustrating and describing a preferred embodiment thereof.

In the drawings—

Fig. 1 is a plan view of the guard member in closed adjusted position for cleaning buttons and small insignia;

Fig. 2 is a plan view of the guard member in closed adjusted position for cleaning large insignia, badges and the like employing a plurality of widely spaced attaching means;

Fig. 3 is a plan view of the guard member in open position ready to be fitted around and under an article to be polished;

Fig. 4 is a sectional view through the guard member as taken on the line 4—4 of Fig. 1; and

Fig. 5 is a plan view of the complementary guard pieces shown disassembled.

Referring to the drawings, the improved polishing guard comprises complementary guard members A and B advantageously formed of thin sheet material, for example sheet metal,

plastic sheeting, cardboard and the like. Each of the members A and B may be of general L-shape having an elongated body portion 10 and a lateral offset section or leg 11 at one end thereof. The members A and B are assembled together in opposed relation with the offset legs 11 at opposite ends of the assembly and each underlying or overlying, as desired, an adjacent body portion 10 of the other guard member. The adjacent edges of the assembled members A and B thus present open recesses defined by the inner edge 12 of the leg 11 and the inner edge 13 of the body portion 10.

These guard members A and B are connected in assembled relation so that they may be adjusted longitudinally relative to each other as well as swung about a pivotal axis from relatively open to closed position and vice versa. This advantageously may be accomplished by providing an elongated slot 14 in at least one of the guard members, for example the lateral leg portion 11 of the guard members illustrated herein as the member B, and preferably a similar elongated slot 15 in the end of the body portion

15 opposite the leg 11 of the other member illustrated herein as the member A. The members A and B are pivotally and slidably connected together in assembled relation by a loose slideable pivot extended through the coinciding slots of the overlapping portions 10 and 11 of the members A and B. This slideable pivot advantageously may comprise a pair of disc-like washers 16, one on each side of the assembled sheets A and B, which washers may be interconnected by a suitable fastener such as a tubular rivet 17.

It will be apparent that the above construction of polishing guard permits the guard members A and B to be swung apart about the pivot extended through the slots 15 to an open position as shown in Fig. 3. The guard members may be swung to closed position under a button or insignia, and shifted longitudinally to encompass the attaching means of the button or insignia as shown in Figs. 1 and 2. In the case of a button or insignia C having a single attaching means c' the guard members are relatively shifted so that the lateral extensions are closer together and partially underlie the button C, as shown in Fig. 1. When used with other insignia having a plurality of spaced attaching means d', for example the insignia of the rank of a major general, indicated by dotted lines D, Fig. 2, the guard member may be longitudinally shifted to separate the extensions, and thus elongate the recess formed therebetween. The combination of the pivot 17 shift-

able in the elongated slot provides for substantial adjustment of the guard members to accommodate attaching means of various spacing, and when registering slots 15 are provided in both guard members, as shown, the range of adjustment is considerably increased.

While I have illustrated and described a preferred embodiment of polishing guard, it is to be understood that the invention is not to be restricted to the specific details thereof, as the scope of the invention is best defined in the appended claims.

I claim:

1. A polishing guard comprising a pair of elongated members of sheet material, at least one of said members being provided with a laterally extended portion adjacent one end thereof adapted to overlap an end portion of the other member, said laterally extended portion and said overlapped portion of said member being each provided with a longitudinally extending slot, and pivot means loosely mounted in said slot for connecting said members together permitting lateral swinging as well as longitudinal shifting of said members relative to each other.

2. A polishing guard comprising a pair of complementary members of sheet material each having a body portion and an extension extending laterally from one side edge adjacent one end thereof, the extension of one of said members and the end portion of the body of the other of said members each being provided with a longitudinally extending pivot means slidably extended through said slots for connecting said members together, said pivot and slots permitting said members to be swung laterally to open and closed position and to be shifted longitudinally relative to each other.

3. A polishing guard for buttons, insignia and the like having attaching means for various spacings comprising a pair of guard members of sheet material each having an elongated body portion and a relatively shorter leg portion ex-

tending laterally from one edge of the body portion adjacent one end thereof, said guard members being adapted to be connected together in opposed partially overlapping relation so that the opposed adjacent edge portions of the body and adjoining edge of adjoining legs cooperate to form an opening for the reception of attaching means for buttons, insignia and the like, the overlapping portions of said guard members at one end of the assembled structure being provided with registering elongated slots, and pivot means slidable in said slots for pivotally connecting said guard members together for lateral swinging movement to open and closed position while permitting longitudinal shifting of said guard members relative to each other to vary the effective length of the attaching-means-receiving opening.

4. A polishing guard for buttons, insignia and the like having attaching means of various spacings comprising a pair of guard members of sheet material each having an elongated body portion and a relatively shorter leg portion extending laterally from one edge of the body portion adjacent one end thereof, said guard members being adapted to be connected together in opposed partially overlapping relation so that the opposed adjacent edge portions of the body and adjoining edge of adjoining legs cooperate to form an opening for the reception of attaching means for buttons, insignia and the like, the overlapping portion of at least one of said guard members being provided with a longitudinally extending slot, and pivot means slidable in said slot for pivotally connecting said guard members together for lateral swinging movement to open and closed position while permitting longitudinal shifting of said guard members relative to each other to vary the effective length of the attaching-means-receiving opening.
